CLAIM

The ornamental design for a cart, as shown and described.

DESCRIPTION

FIG. 1 is a perspective view of a first embodiment of a cart showing our new design;

FIG. 2 is a top plan view thereof;

FIG. 3 is a back elevation view thereof;

FIG. 4 is a front elevation view thereof;

FIG. 5 is a right side elevation view thereof;

FIG. 6 is a perspective view of a second embodiment of a cart showing our new design;

FIG. 7 is a back elevation view thereof;

FIG. 8 is a front elevation view thereof;

FIG. 9 is a right side elevation view thereof; and,

FIG. 10 is a top plan view thereof.

The broken lines shown in the figures are included for the purpose of illustrating portions of the cart which form no part of the claimed design.

1 Claim, 9 Drawing Sheets
